UNITED STATES PATENT OFFICE.

ERRETT I. SHRIMPLIN, OF ALLIANCE, OHIO.

DOOR-HOLDER.

1,188,498.

Specification of Letters Patent. Patented June 27, 1916.

Application filed August 5, 1915. Serial No. 43,713.

To all whom it may concern:

Be it known that I, ERRETT I. SHRIMPLIN, a citizen of the United States of America, and resident of Alliance, county of Stark, 5 and State of Ohio, have invented certain new and useful Improvements in Door-Holders, of which the following is a specification.

This invention relates broadly to door-10 holding devices, and specifically to a device for holding a door in open position.

The primary object of the invention is to provide a simple, durable and inexpensive device whereby doors may be rigidly main-15 tained either in open or closed position.

With this and other objects in view, the invention resides in the features of construction, arrangement of parts, and combinations of elements which will hereinafter 20 be exemplified, reference being had to the accompanying drawings, forming a part of this specification, in which—

Figure 1 is a view showing the invention in top plan applied to double out-25 wardly-swinging doors, as the doors of a garage, one door being shown open and the other closed; Fig. 2 is a front elevation of the same; Fig. 3 is an enlarged side view of the invention detached and folded; Fig. 4 is 30 a front elevation of the same; and Fig. 5 is a section on line 5—5, Fig. 3.

Referring to said drawings, in which like designating characters distinguish like parts throughout the several views—1 and 2 in-35 dicate two similarly formed arms adapted to fold side by side one against the other and connected by a pivot-pin 3, said arms constituting a flexible brace. When in folded position the adjacent faces of said arms co-40 incide except at their outer ends, as shown at the right hand side of Fig. 2 and in Fig. 3, said ends being curved outward slightly in divergent directions to form an open space 4 therebetween. Pivots connected to 45 the outer end of the arm 1 are the extremities of a clevis-shaped shackle or stirrup 5 the head of which is connected by an eyebolt 6 to the body portion of a bow-shaped bracket 7 the terminals of which are adapted to be 50 mounted on the under side of the top 8 of a door frame. Said eyebolt connection permits swivel-like movement of the stirrup 5 with respect to the bracket 7. Thus, a universal joint is constituted between the arm 55 1 and said bracket.

Pivots connected to the outer end of

the arm 2 are the terminals of a yoke 9 the head of which is pivotally attached to a plate 10, said yoke and plate constituting the members of a hinge connected by a pintle 60 11. Said plate 10 is adapted to be rigidly mounted on the inner face of a door 12 adjacent both to the outer lateral and upper edges of the latter, as shown.

The body portions of the arms 1 and 2 are 65 preferably grooved or channeled on their outer faces, as shown at 13, thus decreasing the weight of said arms without materially sacrificing the strength thereof. The pivot- 70 pin 3 has its head seated at the bottom of the channel of one of said arms and has its opposite end extended through a bow-shaped spring 14 which has its ends slidably seated in the channel of the opposite arm. By adjustment of the nut 15 on the 75 projecting threaded end of said pivot-pin the tension of the spring 14 is regulated. Said spring is designed to permit of out- 80 ward yielding movement of said arms with respect to each other to permit of a short longitudinal rib 16 carried on the inner face of one of said arms to rise, during the turning movement of said arms to and from extended position, from a corresponding groove 17 provided therefor in the other 85 arm. When the arms occupy either extended or folded positions said rib lies seated in said groove, thus maintaining said arms more or less rigidly against relative move- 90 ment.

As will be obvious from the foregoing description, the device serves as a brace by which an open door is maintained against chance closing movement as shown at the left hand side of Figs. 1 and 2. However, 95 when it is desired to close the door, a slight downwardly directed force applied near the point of pivotal connection of the arms one with the other will suffice to start the folding movement which may be completed by 100 slight closing force applied to the door. When the door occupies closed position, as shown at the right hand side of said Figs. 1 and 2, the arms are folded together and occupy a suspended vertical position. In 105 moving to and from folded position the necessary movement of the arms 1 and 2 is permitted by the universal-joint character of the connections between their outer ends and the building structure.

From the foregoing description it will be seen that simple and efficient means are pro-

vided for accomplishing the objects of the invention; but, while the elements shown and described are well adapted to serve the purposes for which they are intended, it is to be understood that the invention is not limited to the precise construction set forth, but includes within its purview such changes as may be made within the scope of the appended claim.

10 What is claimed is—

10 A door holder comprising a pair of pivotally connected foldable arms, said arms having their outer ends curved laterally in opposite directions, a bracket for mounting 15 on the under side of the head of a door frame, a stirrup having its head swiveled to said bracket and having its extremities piv-

oted to the curved end of one of said arms, a plate for mounting on a door, and a yoke having its head hinged to said plate and 20 adapted to fold laterally toward and away from the latter, said yoke having parallel terminals pivotally connected to the curved end of the other of said arms, the connections for said arms being adapted to permit 25 the latter to swing to and from a vertically suspended folded position.

In testimony whereof, I affix my signature in presence of two subscribing witnesses.

ERRETT I. SHRIMPLIN.
